UNITED STATES PATENT OFFICE.

HENRY STANLEY, OF ST. LOUIS, MISSOURI.

METHOD OF ROUGHENING AND CORRUGATING THE SURFACES OF GRINDING-ROLLS.

SPECIFICATION forming part of Letters Patent No. 357,872, dated February 15, 1887.

Application filed November 30, 1886. Serial No. 220,328. (No specimens.)

To all whom it may concern:

Be it known that I, HENRY STANLEY, of the city of St. Louis, in the State of Missouri, have invented a certain new and useful Method of 5 Roughening the Surfaces of Grinding-Rolls, of which the following is a full, clear, and exact description.

While smooth chilled-iron rolls are generally used in milling, they can be improved by a 10 roughened surface, such surface giving better results in the manufacturing of flour.

In carrying out my method or process I take a metallic roll, when the grinding-surface has been otherwise finished, and treat the surface 15 with dilute nitric acid, which will have the effect of giving a roughness to the surface very much resembling that of a porcelain roll. Any other acid or other material may be used that will, by corrosion of the metal, cause the rough- 20 ening of the surface.

The rollers may have a smooth cylindrical surface before treatment, or may be corrugated or have any sort of depressions or projections

before treatment, and the whole of the surface may be treated with the corroding agent; or 25 any particular pattern or lines, dots, or corrugations may be etched in the surface of the roll by covering the surface with some substance which will protect the surface from the action of the acid, the removal of the substance from 30 the lines, dots, or other parts to allow the dilute acid to act on these parts, and the treatment with dilute acid.

After the etching of the surface, as above, the surface may be cleared of the protecting 35 substance and the remainder of the grinding-surface roughened, if desired, by treatment with the dilute acid or other corrosive.

I claim as my invention—

The treatment of the grinding-surface of a 40 metallic grinding-roll with a corrosive or oxidizing material, for the purpose set forth.

HENRY STANLEY.

In presence of—

GEO. H. KNIGHT,
EDW. S. KNIGHT.
